UNITED STATES PATENT OFFICE.

GEORGE S. HILTZ, OF BROOKLYN, NEW YORK, AND WILLIAM F. PURCELL, OF HOBOKEN, NEW JERSEY, ASSIGNEES TO STOCK QUOTATION TELEGRAPH COMPANY, OF NEW YORK, N. Y., A CORPORATION OF NEW YORK.

CURRENT-TRANSMISSION APPARATUS FOR PRINTING-TELEGRAPH AND OTHER SYSTEMS.

Original application filed May 22, 1926, Serial No. 110,850. Divided and this application filed September 27, 1927, Serial No. 222,245.

The present application is a division of our co-pending application, Serial No. 110,850, filed May 22, 1926. The present application relates particularly to a keyboard 5 which is adapted for use in a printing telegraph system.

More particularly the present invention is directed to a keyboard of a novel type, which is particularly adaptable for use in 10 conjunction with an automatic sending apparatus such as a perforated tape controlled transmitter. With certain forms of automatic sending devices, sunflower mechanisms are employed in the transmitters and 15 these sunflower devices are provided with outer contacts, and inner common contacts. Due to the peculiar control which the perforated type automatic sender utilizes for controlling the transmitter action by selecting live spots or contacts on the sunflower, provision must be made for opening and 20 closing at least two separate circuits to the sunflower for each character which is to be sent.

25 In the previous keyboard constructions for printing telegraphs where sunflower devices have been used in transmitters, the keyboard contemplated the selection of single commutator or sunflower spots and accordingly, 30 each key heretofore controlled a single pair of contacts. According to the present invention a novel form of control has been provided wherein each key controls a dual contact structure which is adapted to open 35 or close up by a single operation, at least two circuits to the sunflower instead of one as heretofore.

Further objects of the present invention 40 reside in a simplification of the keyboard structure to the general end that manufacturing costs may be reduced and to the end 45 that the keyboard will operate in a more reliable manner than heretofore.

In the drawings, 45 Fig. 1 is a circuit diagram of the complete system;

Fig. 2 is a plan view of the keyboard by 50 which manual transmission may be effected. Certain of the parts are broken away to 55 show the underlying construction.

Fig. 3 is a cross-section on line 3-3 of Fig. 2.

The general system with which the novel keyboard is particularly adapted to operate is diagrammatically shown in Fig. 1. It 55 need not be herein described in detail as this system forms the subject matter of our co-pending application, Serial No. 110,850, filed May 22, 1926. It is sufficient to state 44—45—37 generally designate the contact structure of the perforated tape sender which 60 control the sunflower which in turn controls the magnetic brake or clutch magnet 109, by means of a clutch relay 110. The pole 65 changers 92—93—103—90 and 94 send impulses to the relays 95—96 and these in turn control the distant ticker or receiver 102 having escapement magnets 104 and a press-magnet 105. Lines 100 and 101 are the supply mains which connect with a suitable 70 source of current. 168 represents a double throw switch which when thrown to the left (to the position shown) connects the automatic sending mechanism to control the transmitter and when thrown to the right 75 cuts out the automatic sender and cuts in the keyboard which forms the subject matter of the present application.

Referring to Fig. 1, the transmitter includes a sunflower device having a wiper 80 115—116 supported on insulating member upon and operated by a shaft 145 in a well known manner. The sunflower comprises outer contacts marked (letters period) A, 85 B, C, D, etc., which are arranged in sets, each set comprising seven contacts. The sets are arranged in succession and the various respective contacts of one set are connected in parallel with the corresponding contacts in the other sets. Thus the contact 90 designated A is electrically connected to I to J and U. Contact B is connected to K, O and V and so on. Wires such as 167¹ and 167² are used for forming such parallel connections. Within the outer contacts A, etc. 95 are inner contacts marked 1, 2, 3, and 4. Each respective inner contact through the wiper, is adapted to be connected with any of the outer contacts of its particular correlated set of outer contacts. Thus contact 1 100

is arranged for cooperation with outer contacts marked (letters period) to G inclusive, contact 2 for H to F inclusive, contact 3 for (letters period) to S inclusive and contact 4 for T to Z inclusive.

Connected to the outer contacts are wires 167^c which lead to the seven left hand contacts 37 of the perforated control sender, this section generally designated 37—44.

10 Connected to the various and successive inner contacts 1, 2, 3 and 4 are the wires 2^a, which through switch 168 connect to the four right hand contacts 37 of the section of the sender being generally designated 37—45.

15 The keyboard which will now be described comprises an insulating base plate 200 (Fig. 3) supporting side walls 201 and provided with studs 202 which support an 20 insulating cover plate 203. Supported below the cover plate and spaced therefrom by studs 204 is an annular member 205. The plunger keys 160, which are disposed in an annular row and which are 28 in number, 25 slidably pass through the cover plate 204 and through the annular member 205 and at their lower ends rest on insulating bars 161 which individually span the ends of inner and outer annular rows of insulated spring 30 contacts 162 and 163. These contacts 162 and 163 extend radially outwardly and inwardly from their respective buses. Preferably the insulating bars 161 are connected and secured to the ends of the contacts 162 and 163 in the manner shown in Fig. 3. Disposed below the respective contacts 163 and 164 and carried by the insulating base 200 are stationary insulated contacts 164 and 165. These parts are so placed that when 40 any key 160 is depressed the two springs 162 and 163 will be carried down into engagement with the corresponding contacts below as will be readily understood.

45 As shown in Fig. 2 the inner spring contacts 162 are electrically connected to the annular bus 166 which bus is electrically connected to current supply main 100, (see Fig. 1) by wire 166^a, resistance 166^b and fuse 166^c. The outer springs 163 are connected to the outer annular bus 167 which bus in turn is connected to the other side of the source of current or to main 101 by a circuit traced as follows. Through wire 110^a, clutch relay magnet 110, wire 101^a and back to main 101. The buses 167 and 166 not only form a source of supply for the respective contacts 162 and 166 but form a support for these spring contacts themselves. The contacts are preferably screw fastened 50 to the respective annular buses. Buses 166 and 167 are preferably supported from the base plate 200 by means of the studs 206—207.

60 The inner fixed contacts 164 are connected in four groups of seven each, each respec-

tive group corresponding to the respective inner contacts 1, 2, 3 and 4 of the sunflower and the groups are connected individually through wires 168^a to the four right hand upper terminals 168^b of the double throw 70 switch 168. The outer contacts 165 are connected in four groups of seven each in exactly the same manner as outer contacts on the sunflower. For connecting the various contacts 165 of one set with those of the other sets, connecting wires 167^a are provided. Suitable wires 167^c also connect these outer contacts 165 with the outer contacts of the sunflower and the wiring 167^c also connects to the corresponding left hand 80 seven contacts 37 of the mercury contact mechanism which is controlled by the perforated tape. The other contacts 37 (to the right in Fig. 1) of the perforated record contact mechanism which are disposed to 85 cooperate with the mercury 45 are connected to the four upper left hand terminals of switch 168, while the four upper central terminals 168^a of the switch 168 are connected with the inner group of sunflower contacts 90 1, 2, 3 and 4 by means of the wires 2^a previously referred to. It will therefore, be seen that when the switch 168 is in the left hand position shown in Fig. 1, the keyboard is cut out of the system, but when the switch 95 is in the right hand position, the mercury contact mechanism which is controlled by the perforated tape is cut out and the keyboard is cut in. Under such conditions with the perforated record contact mechanism cut 100 out, the outer bus 167 then takes the place of the mercury 44, the inner bus 166 takes the place of mercury 45, the four groups of inner contacts 164, take the place of the four right hand mercury or tape contacts 105 37 and the four groups of outer contacts 165 (each comprising seven contacts) take the place of the seven left hand contacts 37. The keys 160 serving to close individually the gaps normally existing between 163 and 110 165 and between 162 and 164 take the place of the perforated tape.

When the switch 168 is thrown to the right, the unison contacts 154—155 which are connected between the main 100 and the 115 lowermost center contacts of the switch are thrown out and at the same time, the circuit of the tape feed magnet 67 is broken at the fifth (from the top) of the left hand switch terminals. Similarly, the lowermost 120 of the right hand switch terminals and the sixth of the center terminals (counting from the top) place a shunt around the repeat magnet 131.

125 It will now be assumed that the switch 168 is in its rightward position to place the control of the transmitter under the keyboard. Assume now that the wiper 115—116 of the sunflower is on sunflower contacts A¹ and the F key is depressed. This closes the 130

keyboard contacts 162—164 and 163—165 corresponding to F, then as soon as the wiper reaches sunflower contacts F and inner contact 2, current flows from main 101 through wire 101^a, clutch relay 110, wire 110^a, to the outer bus-ring 167 of the keyboard; thence across the outer F contacts 163—165 and through wires 167^a, 167^b, 167^c, 167^d, 167^e, outer contact F at the sunflower, wiper 89, 10 inner contact 2, wire 2^a, terminals 168^a and 168^b of switch 168, wire 168^c, inner F contacts 162—164 at the keyboard to inner bus-ring 166 and thence by wire 166^a, resistance 166^b and fuse 166^c to main 100. The circuit of clutch 109 is therefore closed by relay 110 and the wiper is arrested on contacts F, thereby prolonging the impulse then flowing over the line and causing the tickers to print. When another key is depressed a 20 similar cycle of operations is carried out.

As will be seen from Fig. 1, one side of the source of current connects to one annular bus 166 and the other side of the source connects to bus 167, the depression of a single 25 key connects by a single operation one side of the source selectively to the inner contacts 1, 2, 3 or 4 of the sunflower and also selectively connects the other side of the source to a particular contact of an outer set of the sunflower which as before stated, is connected in parallel with the corresponding respective contacts of the other outer sets. In this way, the dual selection is effected at the sunflower. The keyboard circuit controller therefore provides two double 30 circuit controllers with two sets of contacts 163—165 and 162—164. Contacts 163 and 165 are further subdivided into groups corresponding to the groups or sets of outer contacts upon the sunflower and contacts 162 and 164 are also subdivided into groups or sets which in number correspond to the inner contacts upon the sunflower.

To bring the tickers and transmitter into 40 unison the operator simply keeps his hands off the keyboard, thereby keeping all keyboard circuits open and causing the wiper to rotate uninterruptedly, until he sees the type wheel of his own ticker brought to rest by its unison mechanism. He then depresses the "letters period" key (the upper period key in Fig. 2, corresponding to the letters period contacts on the sunflower); whereupon the wiper is arrested on the letters period contact the next time it comes to that contact, and the tickers all print a period, exactly as if he had depressed the unison key on the punching mechanism.

At the center of the keyboard, Figs. 2 45 and 3, is a repeat key 168^x, by which the normally closed contacts 169, 170, can be separated. These contacts are in series with the normally closed repeat contacts 133, 137, hence to repeat a letter without causing the 50 sunflower wiper to make a complete revolution, the operator simply holds down the key of the letter which he desires to repeat (thereby keeping the wiper stationary) and depresses the repeat key 168^x. This opens the line circuit, which de-energizes the press 70 magnet 105 and therefore causes the tape (at the ticker) to be advanced one letter-space. He then releases the repeat key, thereby closing the line again, which re-energizes the press magnet and causes the 75 same letter to be printed again. Evidently this operation will be repeated as long as he depresses and releases the repeat key.

It will be observed that the keys of the transmitter keyboard, Fig. 2, bear letters 80 and numerals, and that there are two period keys. As is the practice with this particular system, a period is used after every word or number in lieu of a blank space, and advantage is taken of this use to select either 85 a row of characters on the ticker type wheel. Suppose for example that "erie/PF/43/steel/127½" is to be printed, after erie is printed the "letters period" is transmitted, because the characters (PF, signifying preferred) next to be transmitted are letters and hence the same row of characters is used as was employed for printing erie. But when PF has been printed the next characters are numerals and hence the other row 90 must be used. Accordingly, after PF the "figures period" is transmitted. This letter, by means such as described in Hiltz, Patent No. 1,085,125, brings to the impression point 95 the period which is in the figures row and just before the imprint is made, causes the figures row to be selected, so that the figures period is printed after PF and the ticker is left in condition to print figures. Having printed "43" the operator must shift 100 back to the letters row in order to print the word "steel" and he therefore, after "43", transmits the letters period. Again after "steel" is printed he transmits the figures period so that the "127½" can be 105 printed.

We claim:

1. A keyboard adapted for use in a printing telegraph system with a sunflower type transmitter comprising a plurality of depressible keys, of a plurality of electrical circuit controllers controlled by a single depressed key, one circuit controller being adapted to select a particular circuit from one side of a source of current and another circuit controller being adapted to select another circuit from the other side of the source of current.

2. A keyboard for use in controlling a transmitter, of a printing telegraph comprising a group of circuit controllers arranged in sets and comprising key actuated contact elements and cooperating contact elements, means electrically connecting all of certain said elements together, and means 125 130

electrically connecting groups of the other elements in common circuits to form distinct sets, each set having its elements electrically connected to each other but being disconnected from the other sets, another group of circuit controllers also arranged in corresponding sets and comprising key actuated contact elements and other cooperating contact elements, means electrically connecting certain of said elements in a common circuit, and means electrically connecting the other elements in parallel with respective like elements in the other sets, a plurality of depressible keys, and means controlled by the depression of a single key for actuating the corresponding key actuated contact elements of both circuit controllers at a single key operation.

3. A keyboard for use in controlling the transmitter of a printing telegraph comprising in combination a plurality of depressible keys and cooperating circuit controlling and selecting means with provisions for effecting a dual selection in a common circuit by and upon the operation of a single key.

4. A keyboard for use in controlling the transmitter of a printing telegraph comprising in combination, a plurality of depressible keys, a plurality of circuits to be controlled thereby comprising one group of circuits selectively controlled by a depressed key to selectively establish a circuit relation therebetween to a common line, and another plurality of circuits constituting another group which also receive current from a common line, said respective first and second mentioned common lines receiving current of opposite polarity, and means operable upon the depression of the same aforesaid key for selectively connecting one of the aforesaid last mentioned circuits to its common line.

5. A keyboard for use in controlling a printing telegraph transmitter which has in combination with a group of circuits individually connected to contact elements of a sunflower, and another group of circuits individually connected to other contact elements of the sunflower which are disposed in sets corresponding to the first mentioned contacts and in which corresponding contacts of the respective sets are connected in parallel, a plurality of depressible keys, and means controlled by and upon the depression of a single key for effecting a selective interconnection of a source of current with one of the first mentioned group of circuits and with one of the second mentioned group of circuits to ultimately select a circuit and in accordance with the conjoint selective interconnection of the source to both groups of circuits.

6. A keyboard for use in connection with printing telegraph transmitters, comprising in combination with a plurality of depress-

ible keys, of a plurality of depressible key actuated contacts, said contacts being in distinct sets, and a pair of contacts one in each set being actuated upon the depression of a single key, other contacts arranged in sets and disposed to cooperate with the respective sets of key actuated contacts, means interconnecting each set of key actuated contacts in a distinct common circuit, means electrically interconnecting a number of the other contacts to form a number of individual groups, each containing a like number of contacts with all of the contacts of each respective group connected together to a circuit which pertains to that group, and means interconnecting the respective contacts of the other set of said other contacts to form a number of parallel sets.

7. A keyboard for use in controlling a printing telegraph transmitter, comprising a plurality of annularly disposed depressible keys, a plurality of annular rows of fixed contacts radially extending and annularly disposed pairs of blade contacts under the keys arranged to be displaced in unison by the depression of a single key into contact with pairs of individual fixed contacts.

8. A keyboard for use with a printing telegraph transmitter comprising in combination a pair of annular buses, one receiving current at one polarity from a source and the other receiving current at opposite polarity from said source, a plurality of sets of key actuated contacts carried thereby, each set being carried by and electrically connected to its own associated bus, and a plurality of individual contacts arranged in pairs for cooperation with respective pairs of key actuated contacts and plurality of depressible keys for effecting the conjoint operation of a pair of key actuated contacts, one being in one set and the other in the other set.

9. A keyboard for use with a printing telegraph transmitter comprising in combination a plurality of depressible keys, a plurality of sets of key actuated contacts arranged in pairs, each pair being conjointly operable by the depression of a single key, a plurality of annular buses one for each set of key actuated contacts and each constituting a separate common conductor for the contacts of its respective set, and a plurality of sets of other contacts disposed in pairs for cooperation with the pairs of key actuated contacts upon their actuation.

10. The invention set forth in claim 9 in which each set of the contacts which cooperate with the key actuated contacts are further subdivided into a plurality of groups, and in which the various contacts of one group of one set are all also electrically connected in a common circuit and in which the various contacts of another group of the other set are electrically connected in

parallel with the corresponding contacts of the other groups of the same set.

11. A keyboard for use with a printing telegraph transmitter, comprising in combination a pair of annularly and concentrically disposed bases each insulated from the other, blade spring contacts disposed radially outwardly and inwardly from the aforesaid bases, an annularly disposed series of depressible keys arranged to depress said spring contacts in pairs by the depression of a single key, and a plurality of annular rows of fixed contacts disposed under the blade contacts and arranged in pairs to individually contact with a respective blade contact upon their actuation by a single key.

12. A keyboard adapted for use in controlling the transmitter of a printing telegraph comprising in combination a plurality of depressible keys and cooperating circuit controlling and selecting means controlled thereby, said means comprising a plurality of key actuated contacts constituting a set of contact pairs, one side of said entire set of contact pairs being connected in common to one side of a source of current and the other cooperating contacts of said pairs being individually connected to separate circuit lines which include a number of parallel lines, another plurality of key actuated contacts constituting different other sets of contact pairs having one side of all of the pairs of said sets connected in common to the other side of the aforesaid common source of current and having their other cooperating contacts of the pairs of each of the sets connected together and to lines which are ultimately completed through the aforesaid lines related to the other set of contacts to thereby provide a selection by the operation of a single key of circuit relations which in number represent the product of the number of key actuated contact pairs in one set times the number of other sets of contact pairs of the other set.

13. A keyboard for use in controlling the transmitter of a printing telegraph comprising in combination a plurality of depressible keys and cooperating circuit controlling and selecting means operated by and upon the operation of a single key, said circuit controlling and selecting means comprising a certain group of circuit controlling and selecting instrumentalities adapted to selectively establish various circuits to one side of a common source of current by key action and another group of circuit controlling and selecting means being likewise adapted by the action of the same single key to selectively connect other circuits to the other side of the same common source of

current whereby the ultimate circuit selection is conjointly controlled by the circuits which are established from one side of the source as modified by the circuit relations which are established with the other side of the same source.

14. A keyboard for selectively establishing circuit relations to a sunflower transmitter in a printing telegraph system wherein individual complete circuits include parallel circuits to correspondingly disposed contacts of certain sets of sunflower contacts and wherein other circuits extend to other cooperating sunflower contacts and comprising in combination, a plurality of depressible keys, and means brought into operation by the depression of a single key for selectively establishing circuit relations from one side of a source of current to a particular circuit of the first of the aforementioned circuits, and means also brought into operation by the depression of the same key for also selectively establishing selective circuit relations from the other side of the same source to one of the second mentioned circuits whereby the selection of the ultimate circuit at the sunflower is controlled conjointly by the dual selection effected at both sides of the common source of current.

15. A keyboard transmitter for a printing telegraph comprising in combination with a plurality of depressible keys, a plurality of groups of circuit controllers, each group comprising a plurality of sets of key actuated contact devices, the contact devices of one group having the corresponding individual contacts in the respective sets connected in parallel, and the contact devices of the other group having the individual contacts of each set connected in common to a circuit which is individual to each set, and means brought into operation by and upon the depression of a single key for concurrently closing individual contacts in both groups of circuit controllers.

16. A keyboard device for a printing telegraph with depressible keys and circuit controlling means controlled thereby, a multiplicity of circuits associated with said circuit controlling means, said circuit controlling means having provisions brought into operation by the depression of a single key for effecting circuit selections to the aforesaid circuits in a dual manner so that one selection of the circuits coordinates with another selection of the circuits for the ultimate establishment and selection of a single controlling circuit.

In testimony whereof we hereto affix our signatures.

GEORGE S. HILTZ.
WILLIAM F. PURCELL.
